UNITED STATES PATENT OFFICE.

WILLIAM ABRAMS, OF CHICAGO, ILLINOIS.

DESIGN FOR A SPINDLE FOR LIGHTING FIXTURES.

Application filed January 5, 1925. Serial No. 11,923. Term of patent 3½ years.

To all whom it may concern:

Be it known that I, WILLIAM ABRAMS, a citizen of the United States, residing at Chicago, in the county of Cook and State of Illinois, have invented a new, original, and ornamental Design for a Spindle for Lighting Fixtures, of which the following is a specification, reference being had to the accompanying drawings, forming part thereof.

Figure 1 is a view in elevation, and Figure 2 is an edge view showing my new, original and ornamental design for a spindle for lighting fixtures.

I claim:

The ornamental design for a spindle for lighting fixtures as shown.

WILLIAM ABRAMS.
